UNITED STATES PATENT OFFICE.

LEON C. ORCUTT, OF SYRACUSE, NEW YORK, ASSIGNOR, BY MESNE ASSIGNMENTS, TO UNITED STATES HOFFMAN MACHINERY CORPORATION, OF NEW YORK, N. Y., A CORPORATION OF DELAWARE.

PRESSING MACHINE.

Application filed April 17, 1922. Serial No. 553,742.

This invention relates to presses and especially garment pressing machines. More particularly the invention relates to improvements in automatic press opening means.

5 An object of this invention is to produce an improved pressing machine having an automatic opening means or a trip means which causes the press to automatically open immediately following the release of the machine from high pressure.

In this class of garment pressing machinery it is usual to employ motive power to produce final high pressure subsequent to the closing of the press; and it is necessary to 15 provide locking means to prevent an operator from releasing or opening the press during the high compression period in order that the machine will not be damaged. It has been the practice to employ an operator operated 20 device for opening the press immediately following the relief of high pressure, but in my improved pressing machine, there is provided automatically operated means for tripping the opening mechanism so that the press will 25 open, in an automatic manner, immediately following the relief of the machine from high pressure, thus saving the operator the effort required in opening the press.

In the accompanying drawings I have illustrated two practical embodiments of my invention, but it is to be understood that I claim a right of protection as to all such changes as may come within the scope of my invention.

Figure 1 illustrates a typical garment press 35 in side elevation with the improvements constituting my invention embodied therein. In this view the press is shown in high pressure position.

Figure 2 is a similar view differing from 40 Figure 1 in that the press is relieved from high compression, the position of the parts being such that the press operating mechanism is in the act of being released or kicked off to open up the press. Figure 3 is a sectional view taken on the line 3—3 of Figure 2.

Figure 4 is a fragmentary view of another 45 form of my invention wherein automatic releasing means is combined with operator controlled releasing means; and Figure 5 is a sectional view on the line 5—5 of Figure 4 to show the relation of the release pedal with the closing pedal.

A pressing machine constructed in accordance with the plans of my invention has both

an operator controlled and automatic press 55 opening means. The automatic means is power driven or mechanically actuated and functions to open the press simultaneously with the release of the machine from high pressure so that attention and effort of the 60 operator is not required; and in addition to this automatic means, a kick-off device is employed whereby the operator, if he wishes, may open the press in case the automatic means for any reason fails to function or is 65 not used.

The frame 6 of the pressing machine carries the work support or buck 7; and a press lever 8 is fulcrumed at 9 on the frame. A press head 10 is carried on the front end of 70 the press lever; and a toggle, consisting of pivoted links 11 and 12, is pivoted on the rear portion of the press lever for swinging the lever 8 to open and close the head 10 against the buck 7. The ends of the toggle are pivoted 75 at 13 on the press lever and at 14 to a cam follower 15, and the cam follower is pivoted on a pin 16 fixed to the frame. A shaft 17 has fixed thereto a cam 18 which carries a roller bearing 19, the outer race of which is 80 secured in the cam follower 15. Any suitable gear transmission, driven by an electric motor or otherwise, may be supplied to rotate the shaft 17 to drive the cam follower 15 up and down through a short movement to elevate 85 and lower the vertical toggle 11—12.

A toggle comprising links 21 and 22 has its ends pivoted at 23 on the frame and at 24 on the vertical toggle. A pedal 25 is swung in the frame, and as shown in the drawings, 90 is pivoted on the power shaft 17. A connecting rod 26 joins the pedal and horizontal toggle 21—22 in working relation. A coil spring 27 has one end anchored to the frame and the other end anchored to the toggle for facilitating the lifting of the head 10 when the two toggles are broken.

Referring to Figure 4, a kick-off pedal 28 is pivoted in the frame on a pin 29, and this kick-off pedal has its rear end 30 sufficiently weighted to cause it to normally drop down against the floor or frame of the press, but for the purpose of this description it is shown held in horizontal position. The kick-off pedal has a projecting lug 31 which extends out under the lower edge of the pedal 25 so that the lug strikes the pedal causing it to move upwardly, thus breaking the horizontal

toggle 21—22, which in turn collapses and draws inwardly on the toggle 11—12 to raise the press head 10.

The cam follower has an integral arm 35 projecting upwardly and adapted to swing about the pin 16. A locking lever 36 is pivoted at 37 on the frame and has its upper end connected with the aforesaid arm 35 through a draw-rod 38. The lower end of the locking lever 36 carries an adjustable screw or part 39 adapted to engage the rear end of the kick-off pedal 30 whereby this pedal is positively held against kick-off movement during the time the press is under high compression, at which time the position of the parts are as shown in Figure 4. This position of the locking lever relative to the kick-off pedal 28 is brought about by the rearward swing of the arm 35 during the upward movement of the cam 18 and cam follower 15 which draws the rod 38 rearwardly and swings the locking lever part 39 into the path of the kick-off pedal 30.

As soon as the cam 18 is turned downwardly, the draw-rod 38 moves forwardly to swing the locking lever 36 out of the path and away from the kick-off pedal 28 so that an operator may depress the kick-off pedal 28 producing an upward thrust on the pedal 25 to open the pressing machine.

Describing further the form of my invention shown in Figure 4, a release device 32 is pivotally carried on the pin 29, and this device 32 has a lug 33. A pawl 45 is pivoted on a pin 46 to the pedal 25. This pawl is normally held in vertical position against a lug 47 by a spring 48. As the release device swings its lug 33 downwardly, the lower end of the pawl 45 pivots rearwardly to allow the lug 33 to pass, and immediately thereafter the pawl 45 springs back and stands in vertical position. A draw-rod 33^a connects the upper end of the locking lever 36 with the upper end of the release device 32 whereby the motion of the locking lever is transmitted to the release device. In the operation of this particular form of the invention, the cam follower arm 35, during its rearward or left-hand movement, pulls the rod 38 in the same direction to swing the lug 33 down below the pawl or catch device 45 and at this stage the machine is under high compression. During the next cycle of operation the cam 18 swings down and moves the draw-rods 38 and 33^a forwardly to drive the lug 33 up against the pawl 45 to quickly cause the press to open, and during this movement it is noted that the lock part 39 moves away from the pedal 28 whereby the operator is free to depress the treadle 28 to open the press if for any reason the automatic opening means 32 is not used.

Referring now to the other figures of the drawing, there is shown an automatic release

lever 42 pivoted on a pin 43. The lower outer end of this release lever carries a fixed lug or pin 44 which is in line with a pawl 45 pivoted at 46^a on the pedal 25. The pawl 45 is held in normally vertical position against a shoulder 47^a through the agency of a coil spring 48^a. The lug 44 on the release lever freely passes the pawl 45^a on its downward swing because the spring yields and allows the lug to trip by until it assumes a position underneath the lower end of the pawl, as shown in Figure 1. When, however, the release lug 44 moves upwardly it impinges the bottom end of the pawl which causes the pedal 25 to be quickly driven upwardly, thus breaking the two toggles and opening the press. A draw-rod 49 connects the upper end of the release lever 42 with the arm 35 and is actuated by the cam follower 15 to swing the release lug 44 upwardly to open the press after the cam is moved to its downturned position shown in Figure 2.

A garment press of this class is sometimes used without the motor, for the closing power of the pedal 25 is substantially great, and produces pressure adequate for some classes of work. It is to be noted therefore, that on some occasions the machine would not be operated by power, and therefore the power release mechanism would not function. The kick-off pedal 28 is therefore provided for the purpose of opening the press by foot-power when the power means or electric motor drive is not employed.

The apparatus comprising my invention is simple in construction and operation and provides a press with either a pedal opening means, or an automatic opening means, or a combination of both such means, and facilitates the work of the pressing machine.

What I claim is:

1. In a garment pressing machine, the combination of co-operative pressing members; means for closing the press; means for forcing the members into high pressure relation after the press is closed, and for relieving the press of high pressure; a release treadle; a locking device cooperating therewith and positioned by the high pressure exerting means to prevent the pressing members from being released by the operator while under high pressure; and means for automatically opening the press when the high pressure is relieved.

2. In a garment pressing machine, the combination of cooperative pressing members; operator-actuated means for closing the press; means acting when the press is closed to force the pressing members into high pressure relation and for relieving the press of high pressure; a release treadle; a locking device positioned by the high pressure applying means and cooperating with the release treadle to prevent actuation of

- the latter; a release device; a connection between the release device and the locking device; and means actuated by said connection and the release device to open the press.
5. 3. In a garment press, the combination of cooperative pressing members; operator-actuated means for closing the press; means acting when the press is closed to force said pressing elements into high pressure relation; a release treadle; a locking device co-operating therewith to prevent the pressing members from being accidentally and suddenly released while under high pressure; a mechanism operated by the high pressure 60
- 10 producing means for unlocking the locking device; and a trip operated by the high pressure mechanism for automatically opening the press.
4. In a garment pressing machine, the combination of co-operative pressing members; a pedal to actuate one of the pressing members; a release treadle; means for forcing the members into high pressure relation; a locking device acting upon the release treadle to prevent the pressing members from being accidentally and suddenly released while under high pressure; means actuated from the high pressure producing means to position the lock; a pawl on the pedal; a lever 70
- 25 adapted to trip past the pawl in one direction when the press is moving into high pressure position; and means operated by the pressure producing means for swinging the lever in the opposite direction against the pawl to 80 open the press when the same is relieved of high pressure.
5. In a garment pressing machine, the combination of cooperative pressing members; means for closing the pressing members; means for forcing the members into high pressure relation; a release treadle; a locking device acting thereon and operated by the high pressure producing means to prevent the pressing members from being accidentally and suddenly released while under high pressure; a trip lever cooperating with the closing means to open the press; and a connection established between the trip lever and the locking device whereby the locking device when moved to an unlocked position causes the trip lever to open the press.
6. In a garment pressing machine, the combination of co-operative pressing members; means for closing the pressing members; mechanism for forcing the members into high pressure relation; a bell crank trip 90
- 20 device; an abutment carried on an element of said closing means; and a connection between the trip device and said mechanism for driving said trip device against the abutment to 100 open the press.
7. In a garment pressing machine, the combination of cooperative pressing members; means for closing the press; mechanism for forcing the members into high pressure relation; a trip lever for opening the press; a pawl carried on an operative part of the press closing means and co-operative with the trip lever to permit said lever to pass in closing movement of the press closing means and 110 to abut the same while moving in the opposite direction; and mechanism for driving said trip device against the pawl to open the press.
8. In a garment press, the combination of cooperative pressing members; toggle linkages to operate the same; a treadle to actuate the toggle linkages; a trip pedal to break the toggle linkages; a lock to engage the trip pedal when the machine is undergoing pressing strain; and an automatic trip device, acting on the treadle, to open the machine upon release of the pressing strain.
9. In a garment press, the combination of cooperative pressing members; toggle linkages to operate the same; a treadle to operate the toggle linkages; a cam follower connected with the toggle linkages to impose a final pressure; means to operate the cam follower; an arm carried by the cam follower; 85 a trip lever cooperative with the treadle to open the press; and a connection established between the arm and trip lever for actuating the latter.
10. In a garment pressing machine, the combination of co-operative pressing members; a set of toggles to open and close the press; a pedal lever to operate the toggles to close the press; a cam follower working in conjunction with the toggles to impose final 100 high pressure upon the pressing members; a release device for breaking the toggles; a pawl mounted upon the pedal lever adapted to move past said release device as the press is closed; and a connection between the release device and cam follower to drive the release device against the pawl to automatically open the press.

In testimony whereof I affix my signature in the city of Syracuse, New York, this 10th day of March, 1922.

LEON C. ORCUTT.
